UNITED STATES PATENT OFFICE.

MATTHIAS BROCK, OF ROXBURY, MASSACHUSETTS, ASSIGNOR TO UNITED SHOE MACHINERY COMPANY, OF PATERSON, NEW JERSEY, A CORPORATION OF NEW JERSEY.

MOLDING-MACHINE.

1,130,138.

Specification of Letters Patent.

Patented Mar. 2, 1915.

Application filed May 15, 1912. Serial No. 697,442.

To all whom it may concern:

Be it known that I, MATTHIAS BROCK, a citizen of the United States, residing at Roxbury, in the county of Suffolk and State of Massachusetts, have invented certain Improvements in Molding-Machines, of which the following description, in connection with the accompanying drawings, is a specification, like reference characters on the drawings indicating like parts in the several figures.

This invention relates to stiffener molding or shaping machines and is herein illustrated as embodied in a machine for forming heel stiffeners comprising a mold, a support for a stiffener, a die mounted in said support, means for causing said mold and support to approach each other, and means for causing the die to enter the mold.

0 A feature of the invention consists in means for gripping the margin of a stiffener and means for bending upwardly and molding in that position the forward portions of said margin.

25 Another feature of the invention consists in a support for a stiffener, means for clamping the sides of the stiffener against the support and means for bending upwardly and molding in that position the forward portions of said margin.

30 A further feature of the invention consists in means for snipping the margin of the forward portion of a stiffener to form a tongue, and means for bending upwardly and molding in that position the tongue so formed.

These and other features of the invention including certain details of construction and combinations of parts will be described in 40 connection with an illustrative machine and pointed out in the appended claims.

45 Referring now to the accompanying drawings, Figure 1 is a perspective of a machine in which the present invention is embodied; Fig. 2 is an elevation of the upper portion of the machine; Fig. 3 is a detail section showing the connection between the carrier, the cross-head and the actuating mechanism; Fig. 4 is a perspective showing the support for the counter, and the mold and die which coöperate to form the upturned lip; Fig. 5 is a fragmentary sectional view of the parts illustrated in 50 Fig. 4, a heel stiffener having an inturned

margin being shown in place upon the support; Fig. 6 is a similar view showing a mold and die in operative relation, portions of the margin of the heel stiffener having been bent upwardly; Fig. 7 is a perspective of a finished stiffener; Figs. 8 and 9 are 60 perspective views of the carrier and the cross-head respectively; Fig. 10 is a perspective of a modified form of mold and die, and Fig. 11 is a perspective of a finished stiffener produced by the action of the mold 65 and die shown in Fig. 10.

Mounted in the frame of the machine are two upright rods 1 which carry at their upper ends between screw-threaded collars 3 and nuts 5 a cross-beam 7, the vertical position of which may be varied by varying the position of the nuts and collars. At the lower central portion of said cross-beam is formed an undercut slot or guideway 9 in which fits a suitably shaped guide 11 carried by 70 a mold 13. This mold (see Fig. 4) comprises two grooves or die cavities 15 which are separated from the sides of the mold by flat gripping faces 17. Arranged to coöperate with the mold is a support 19 and a die 21, said 80 die, in the illustrated embodiment, being slidably mounted in the support and having a stem 23 which projects below it. The die is also provided with two upstanding ribs 25, the outer edges of which coöperate with 85 the outer edges of the grooves or cavities 15 of the mold to bend upwardly and mold in that position the forward portions of the inwardly bent margin of the stiffener.

The heel stiffener upon which the illustrative machine is adapted to operate is a partially molded one, its wings or sides having been shaped to conform to the sides of the heel portion of a last and its margin having been turned inwardly. Referring 90 again to Fig. 4 in connection with Figs. 5 and 6, the operation of the present machine will be indicated. The counter having an inwardly turned margin is placed on the support 19 which has the general shape of 100 the heel portion of a last. The support and the mold are then caused to approach each other until the outer part of the inturned margin of the stiffener is gripped between the flat upper face of the support and the flat faces 17 of the mold, after which relative movement between the die 21 and the mold 13 is brought about to bend upwardly 105

the forward portions of the margin 29 to form the lips 31 shown in Fig. 7 and mold them in that position. It will be noted by referring to Fig. 6 that the outer walls of 5 the grooves 15 in the mold lie in the same plane as the outer walls of the socket 33 and that the outer faces of the ribs 25 are spaced from these planes sufficiently to permit the lips 31 to be forced upwardly as shown in 10 said figure. It will also be noted that if the inturned margin is of sufficient width the upstanding lips 31 will be bent over to an extent at their upper portions and that these bent over portions in the lasted shoe will 15 overlie the top of the ends of the insole lip.

In order to carry out the operation which has been briefly indicated above, the support 19 is provided with sockets to receive pins 35 on a carrier 37, said carrier being 20 yieldingly supported upon a spring 39 coiled about a rod 41 which extends into a bore 43 in the carrier, said bore also being arranged to receive the lower portion of the stem 23 of the die. The rod 41 is adjustably mounted 25 on a cross-head 45 by being threaded through a lug on said cross-head. The screw threads on the lower end of the rod also serve the further purpose of coöperating with a nut 47 to permit adjustment of the 30 tension of the spring 39. The upright arms together with those of the carrier 37 of the cross-head 45 are arranged to slide in guideways in the frame of the machine and are provided with over hanging ends through 35 which are threaded set screws 49 which normally bear upon the upper face of the carrier 37, as shown in Figs. 1 and 2, so that the cross-head and carrier normally move in unison but that upward movement of the 40 cross-head with respect to the carrier is permitted, the carrier being normally held between the spring 39 and the set screws 49. Plates 51, see Figs. 1 and 2, bolted to the frame form one wall of the guideway in 45 which the cross-head and carrier are slideable. In order to reciprocate the cross-head and with it the carrier an arm 53 on an eccentric strap 55 is pivoted at 57 to depending lugs 59 on the cross-head 45.

50 The eccentric 61, which actuates the eccentric strap and arm, is mounted upon a shaft 63 which is rotated by a driving shaft 65 through gears 67 and 69; and preferably a one revolution clutch of any convenient type 55 (not shown) is provided in the driving mechanism and is so arranged that the parts will start from and come to rest in the position shown in Figs. 1 and 2.

It is desirable that means be provided 60 for holding the stiffener securely in place upon the support 19 during the operation of the machine, and to this end jaws 71 having faces which are the converse of the corresponding sides of the support 19 are 65 mounted upon levers 73 which are pivoted

to the carrier 37 at 75, said levers being provided at their lower ends with rollers 77. These rollers are arranged to travel upon cam faces 79 formed on the plates and are held in contact with said faces by a coiled spring 81.

With this construction the operation of the machine is as follows:—A stiffener having an inturned margin is placed upon the support when the parts of the machine are in the position shown in Figs. 1 and 2, and power is applied to the driving shaft 65 to cause it to make one revolution. The upwardly moving arm 53 forces the cross-head 45 with it; and, during the first part of the movement, the spring 81 forces the lower ends of the levers 73 apart thereby clamping the stiffener securely upon the support. The carrier 37 is also moved upwardly through the supporting spring 39 and continues so to move until the support 19 and mold 13 grip the inturned margin of the stiffener. Further upward movement of the carrier is then prevented, and the continued upward movement of the cross-head causes the rod 41 to act upon the stem 23 to force the die upwardly into the mold, this position of the parts being shown in Fig. 6. As the arm 53 moves downwardly the operations described above are reversed, and the parts of the machine come to rest in the position shown in Figs. 1 and 2.

In order to cause the lips 31 to fit closely against the sides of the lip of the insole it may be desirable to snip the inturned margin of the stiffener, a finished stiffener so snipped being shown in Fig. 11, the upstanding lips being indicated at 131. When this type of stiffener is desired, a die 121 is provided the ribs 125 of which have flat faces 83 to provide shearing edges which coöperate with similar shearing edges on blocks 85 which are fastened in the rear portions of the grooves 15 of the mold. The operation of this modification need not be described in detail since it is evident that a mold and die, such as are shown in Fig. 10, may be substituted for the mold and die shown in Figs. 1 and 2. It will be observed, however, that with this form of die and mold the forward portions of the margin of the stiffener are snipped to form tongues and the tongues so formed bent upwardly to produce upstanding lips.

Although the invention has been set forth 120 in connection with a machine adapted to operate upon a partially molded stiffener it should be understood that neither the particular form of the stiffener which is to be operated upon nor the particular construction of the machine which has been shown and described is material to the invention.

In the appended claims the lips 31 will be referred to for convenience as upstanding lips, since they are so shown in the draw- 125 130

, although it should be understood that in the stiffener is incorporated in the shed shoe the lips extend downwardly. Having thus described my invention, what aim as new and desire to secure by Let-
Patent of the United States is:-

1. A machine of the class described having, in combination, a mold, a support for a stiffener, a die mounted in said support, a carrier upon which said support is mounted, cross-head for actuating said carrier, yielding means for causing said carrier to move with said cross-head whereby relative movement between said support and cross-head is permitted, positive means for causing said die to move with said cross-head, and means for actuating said cross-head.

2. A machine of the class described having, in combination, a mold, a support for a stiffener, a die mounted in said support, yielding means for causing said mold and support to approach each other, and positive means for causing the die to enter the mold.

3. A machine of the class described having, in combination, a support for a stiffener having an inturned margin, a die movable with respect to said support, a mold having a portion to coöperate with said support and a second portion to coöperate with said die, and means for causing relative movement between said support and mold to grip said stiffener and for thereafter causing relative movement between said die and mold to bend forward portions of said margin upwardly and mold them in that position.

4. A machine of the class described having, in combination, a support for a stiffener having an inturned margin, a die carried by said support, a mold between which and the support said margin is gripped, and means for causing relative movement between said die and said support to bend upwardly forward portions of said margin and mold them in that position.

5. A machine of the class described having, in combination, means for holding a stiffener having an inturned margin in position to be operated upon, a die, and means for thereafter causing relative movement between said die and holding means to bend portions of said margin upwardly and mold them in that position.

6. A machine of the class described having, in combination, yielding means for gripping the inturned margin of a stiffener, and positive means for thereafter bending upwardly forward portions of said margin and molding them in that position.

7. A machine of the class described having, in combination, means for gripping the inturned margin of a stiffener, and means for thereafter bending upwardly forward portions of said margin and molding them in that position.

8. A machine of the class described having, in combination, a support for a stiffener having an inturned margin, means for clamping the sides of said stiffener against said support, and means for thereafter bending upwardly forward portions of said margin and molding them in that position.

9. A machine of the class described having, in combination, a support for a stiffener having an inturned margin located wholly in a single plane, a carrier for said support, means for pressing said inturned margin against said support, means for thereafter bending upwardly a portion of said margin, clamping members for holding the wings of the stiffener during the upward bending, and means responsive to movement of said carrier for causing said clamping means to approach said support.

10. A machine of the class described having, in combination, a support for a stiffener having an inturned margin located wholly in a single plane, a carrier for said support, means for pressing said inturned margin against said support, means for thereafter bending upwardly a portion of said margin, clamping members mounted upon said carrier for holding the wings of the stiffener during the upward bending, and means responsive to movement of said carrier for causing said clamping means to approach said support.

11. A machine of the class described having, in combination, a support for a stiffener having an inturned margin located wholly in a single plane, a carrier for said support, means for pressing said inturned margin against said support, means for thereafter bending upwardly a portion of said margin, clamping members pivoted to said carrier for holding the wings of the stiffener during the upward bending, and means responsive to movement of said carrier for causing said clamping means to approach said support.

12. A machine of the class described having, in combination, a support for a stiffener, means for clamping said stiffener upon said support, a die, a mold, and automatic means acting successively to actuate the clamping means, to bring the support and mold together, and to cause the die to enter the mold.

13. A machine of the class described having, in combination, means for supporting a stiffener having an inturned margin, means for snipping the margin of the stiffener to form a tongue, and means for thereafter bending the tongue upwardly to form an upstanding lip.

14. A machine of the class described having, in combination, means for supporting a stiffener having an inturned margin, means for snipping the inturned margin of the stiffener to form a tongue, and means

1,150,148

for thereafter bending the tongue upwardly to form an upstanding lip.

15. A machine of the class described having, in combination, a support for a stiffener, a mold and a die provided respectively with a rib and a cavity which co-operate to mold a portion of the margin of said stiffener, and with coöperating shearing edges which act to slit said margin, means for holding said stiffener against said mold, and means for causing relative movement between said die and mold.

16. A machine for operating upon a stiffener having an inturned margin comprising a mold and a die provided respectively

with a rib and a cavity which coöpera bend a portion of said margin upwa and with coöperating shearing edges w act to sever the inturned from the upto portion, means for holding said stiffener against said mold, and means for causing relative movement between said die and mold.

In testimony whereof I have signed my name to this specification in the presence of the two subscribing witnesses.
